(57) **CLAIM**

The ornamental design for a vaporizer device, as shown and described.

DESCRIPTION

FIG. 1 is a top, front, and right side perspective view of a first embodiment of a vaporizer device of our design; FIG. 2 is a bottom, rear, and left side perspective view thereof;

FIG. 3 is a rear view thereof;

FIG. 4 is a front view thereof;

FIG. 5 is a right side view thereof;

FIG. 6 is a left side view thereof;

FIG. 7 is a bottom view thereof; and

FIG. 8 is a top view thereof.

FIG. 9 is a top, front, and right side perspective view of a second embodiment of a vaporizer device of our design; FIG. 10 is a bottom, rear, and left side perspective view thereof;

FIG. 11 is a bottom, front, and left side perspective view thereof;

FIG. 12 is a rear view thereof;

FIG. 13 is a front view thereof;

FIG. 14 is a right side view thereof;

FIG. 15 is a left side view thereof;

FIG. 16 is a bottom view thereof; and

FIG. 17 is a top view thereof.

FIG. 18 is a top, front, and right side perspective view of a third embodiment of a vaporizer device of our design;

FIG. 19 is a bottom, rear, and left side perspective view thereof;

FIG. 20 is a bottom, front, and left side perspective view thereof;

FIG. 21 is a rear view thereof;

FIG. 22 is a front view thereof;

FIG. 23 is a right side view thereof;

FIG. 24 is a left side view thereof;

FIG. 25 is a bottom view thereof;

FIG. 26 is a top view thereof; and,

(Continued)

FIG. 27 is a cross-sectional view of the vaporizer device taken along line 27-27 of FIG. 21 thereof.

The dash-dash broken lines illustrate portions of the vaporizer device that form no part of the claimed design.
